UNITED STATES PATENT OFFICE.

JOSEPH F. KOELMEL, OF CROOKSTON, MINNESOTA.

COMPOUND TOOL.

SPECIFICATION forming part of Letters Patent No. 703,598, dated July 1, 1902.

Application filed March 6, 1902. Serial No. 96,977. (No model.)

To all whom it may concern:

Be it known that I, JOSEPH F. KOELMEL, a citizen of the United States, residing at Crookston, in the county of Polk and State of Minnesota, have invented certain new and useful Improvements in Compound Tools; and I do declare the following to be a full, clear, and exact description of the invention, such as will enable others skilled in the art to which it appertains to make and use the same.

The invention relates to what is known in the art as a "compound" tool, a device comprising within itself several different elements arranged in a simple manner for several different uses, and in the present invention these elements comprise a key-ring, a cork-screw, and a crown cork lifter or remover so arranged with respect to each other that each element may be brought into use for the purpose for which it is designed, and when all are arranged in closed position the tool may be conveniently carried in the pocket.

The object of the invention is to provide a device of this character which shall be simple and compact of construction, durable in use, and comparatively inexpensive of production.

With this and other objects in view the invention consists of certain novel features of construction, combination, and arrangement of parts, which will be hereinafter more fully described, and particularly pointed out in the appended claim.

In the accompanying drawings, Figure 1 is a bottom plan view of my improved tool, showing the parts closed. Fig. 2 is a top plan view of the same. Fig. 3 is a longitudinal sectional view of the parts closed. Fig. 4 is a similar view with the cork-extractor in the position it assumes in use. Fig. 5 is a detail perspective view of the tool. Fig. 6 is a view illustrating the use of the crown-lifter, and Fig. 7 is a detail perspective view of the shield.

Referring to the drawings, 1 denotes the frame of the tool, which frame preferably consists of a bar or strip of spring metal bent to form a bow 1^a and having one end doubled upon itself to form a bail 2, against the side

3 of which the opposite end 4 of the bow has 50 a spring engagement, the extremity of this end being slightly divergent from the side 3 to facilitate the introduction of a key. The frame thus described constitutes a key-ring.

5 denotes a screw pivoted between the sides 55 3 and 6 of the bail and held closed by two springs 7. In closing this screw its point is received and limited in its closing movement by a slotted lug 7', which may be of soft metal—such as lead, copper, or Babbitt 60 metal—so as not to injure the point of the screw. Pivoted also between the sides of the bail is a crown-lifter, a device designed to remove the crown-caps now generally employed for sealing bottles. This lifter is preferably in the form of a hook 8, the bill of which fits the bight of the bail and is inclosed. The rounded portion 9 of said hook is adapted to have a frictional engagement with the bight of the bail and be held in place. 70

10 denotes a shield or cap, which is soldered or otherwise secured around the upper and outer sides of the bail and in addition to serving to brace the bail against expansion due to lateral pressure to which it may be 75 subjected in the withdrawal of a cork or the removal of a crown also serves as a means for receiving a suitable advertisement or the name of the owner of the tool.

The uses of these tools being common and 80 well known it is not thought necessary to enter into a description of the same.

From the foregoing description, taken in connection with the accompanying drawings, the construction, mode of operation, and advantages of the invention will be readily understood without requiring an extended explanation.

Various changes in the form, proportion, and details of construction may be made 90 within the scope of the invention without departing from the spirit or sacrificing any of the advantages thereof.

Having thus described my invention; what I claim, and desire to secure by Letters Patent, is—

The combination with a spring-bow, one end of which is formed with a bail, against

one of the sides of which the opposite end of
said bow has a spring contact or engagement,
of a tool pivoted between the sides of said
bail, and a shield covering the sides and top
5 of said bail and serving to prevent the expan-
sion of the same, substantially as set forth.
In testimony whereof I have hereunto set

my hand in presence of two subscribing wit-
nesses.

JOSEPH F. KOELMEL.
